UNITED STATES PATENT OFFICE.

FRANK A. TITTEMORE AND CHARLES S. RENWICK, OF RICHMOND, CALIFORNIA, ASSIGNEES TO HOPKINS SPRAY EQUIPMENT COMPANY, OF SAN FRANCISCO, CALIFORNIA, A CORPORATION OF NEVADA.

PRESSURE REGULATOR AND TANK COVER FOR PAINT-SPRAYING MACHINES.

Application filed November 7, 1925. Serial No. 67,479.

The present invention relates to improvements in paint spraying apparatus, and more particularly to a pressure regulating means for the paint containing tank in such pressure paint applying systems.

The invention consists primarily in providing a cover of a paint spraying receptacle with pressure regulating means by which the desired pressure may be maintained on the contents of the receptacle to discharge the same therefrom as desired; to provide a means whereby the pressure may be admitted into the receptacle to agitate the contents thereof and to provide a receptacle with means whereby a container as, for example, in the form of a bucket, may be positioned within the main receptacle, and its contents ejected through a separate outlet by the same regulated pressure which acts on the main body of material, thereby adapting the apparatus for two color work.

The invention consists primarily in a diaphragm pressure actuated valve adapted to control an air supply into the receptacle and the operation of the diaphragm by pressure being controlled by the adjustment of tension means.

With the above mentioned and other objects in view, the invention consists in the novel construction and combination of parts hereinafter described, illustrated in the accompanying drawings and pointed out in the claims hereto appended, it being understood that various changes in the form, proportion, size and minor details of construction within the scope of the claims may be resorted to without departing from the spirit or sacrificing any of the advantages of the invention.

In the drawings:—

Fig. 1 illustrates a view in side elevation of the preferred embodiment of our invention, connected with an air pressure means and a spray nozzle.

Fig. 2 is an enlarged transverse sectional view of the cover portion of the paint spray tank.

Fig. 3 is a view in plan of the underside of the cover for the tank.

Fig. 4 is a detail sectional view on line 4—4 of Fig. 3.

Fig. 5 is a detail view in cross section of the front valve 36.

In the drawings, the numeral 1 indicates a conventional motor operating through a drive mechanism 2 and a pump mechanism 3, the latter being connected through a pressure accumulating chamber 4 with a conduit 5 from which leads a hose 6 connected at its end to one end of a through bore 7 in a tank cover 8. The mechanism above is of the type set forth in our issued United States Letters Patent Nos. 1,347,790 and 1,435,761.

The cover 8 is adapted to close the open top of a conventional tank 9 provided with a paint outlet 10 at its base controlled by a valve 11, and from the outlet leads a flexible tube 12 for conveying paint to any well known type of spray gun 13. The gun is supplied with air under pressure through a tubular connection 14 extending from the opposite end of the bore 7 to that with which pipe 6 is connected.

The cover 8 rests on a gasket 15 and is held in position by a suitable clamp mechanism 16. It is provided centrally with an opening 17 and with a lateral extension 18 connecting with the bore 7 approximately midway of its length. The extension terminates in a downwardly disposed nozzle 19 arranged centrally of the opening 17. The lower end of the opening 17 is closed by a sealing member 20 threaded thereinto, the same being provided with a central bore in which reciprocates a valve ring 21 having a scalloped periphery 22, and the center of which is closed by a plug 23 mounting a valve gasket 24 for contacting with the end of the nozzle 19 to close the same.

A coiled spring 25 tends to normally maintain the packing 24 seated against the outlet in the nozzle 19, said packing being carried by a collar against which the spring 25 bears. The lower end of the central opening in the member 20 carries a tubular threaded plug 27, the opening in which is normally closed by a spring seated check valve 28.

Upwardly from the ring 21 extends a stirrup 29 connected with a diaphragm 30 extending across and closing the upper open end of the opening 17. The diaphragm 30 is maintained in position by a cap 31 threaded to the walls surrounding the opening, and said cap at its upper end carries a winged screw member 32 bearing on the coiled

spring 33 interposed between the lower end of the screw 32 and the plate 34 on the upper side of the diaphragm 30.

- Air entering the lateral extension 18 will 5 eject through the nozzle 19 and unseat the member 24 from the end of the nozzle and will accumulate within the tank until such time as the air pressure acting on the underside of the diaphragm 30 overbalances the 10 tension of spring 33 and causes the action of the diaphragm and stirrup to seal the member 24 against the end of the nozzle and preclude further pressure until such time as the pressure in the tank is relieved.
- 15 A gauge 35 connected with the opening 17 indicates the pressure within the opening and tank.

Within the cover is rotatably mounted a plug valve 36 intersecting the lateral extension 18, and this valve is provided with a 20 T bore 37, Fig. 5, which admits of the valve being positioned to permit air to enter the tank through the by-pass 38 with which is connected a pipe 39 extending to a point 25 near the base of the tank, and in this case the entering air maintains the paint in agitation.

The valve 36 is also provided with an inclined bore 39' which is adapted to connect 30 the relief passage 40' with the atmosphere on the proper positioning of the valve.

To enable the application of two color work by air pressure from a single tank, a discharge tube 40 is extended through the 35 tank, its outlet being controlled by a valve 41, and over the end of the pipe is adapted to be positioned a separate container containing the paint or material of a color different from that within the main tank 9, the 40 interior of this latter container being exposed to the air pressure within the tank.

The container cover is a one piece combination head and pressure regulating device equipped with but one valve cock that 45 is so designed that it can control the outside pressure into the diaphragm chamber or release the air contained in the tank into the atmosphere or pass air into the agitator pipe for agitation purposes in container, or control air from entering or exhausting from channels that effect air pressure referred to above.

We claim:—

1. In combination with a fluid containing tank, a removable cover therefor, a receptacle within the tank and containing fluid 55 separate from that in the tank, means for delivering air under pressure into the tank and into the receptacle, said receptacle being at all times open to the air pressure within the tank, fluid outlets for both the tank and receptacle and means for regulating the air admitted to the tank to maintain the pressure therein substantially constant.

2. In combination with a fluid containing 60 tank having a fluid outlet, of a removable cover for the tank having a main passage therein adapted to receive an air supply connection at one end and adapted to receive an outlet connection at the other and having 70 a branch passage leading from said main passage and opening into said tank, an automatic valve within the container for controlling the branch passage at the point of discharge into the container, said valve being under the influence of pressure within the container for the purpose of maintaining a substantially constant air pressure within the container, a single valve in said branch passage for releasing the pressure within 80 the tank when in one position and a pipe for delivering air below the surface of the liquid in the tank to agitate it when said single valve is in its other position.

3. In combination with a fluid containing 85 tank having a fluid outlet, a removable cover for the tank, the same being provided with a divided channel opening into the container and into the atmosphere, and one end adapted for connection with an air supply 90 under pressure, a pressure regulating valve within the channel opening into the container for precluding the admission of air into the tank on the air therein attaining a predetermined pressure, and a manually 95 controlled valve within the channel opening into the tank for positioning to provide a pressure release orifice from the interior of the tank to the atmosphere and for positioning to afford an air inlet into the tank from 100 said channel in advance of said pressure regulating valve.

In testimony whereof we have signed our names to this specification.

FRANK A. TITTEMORE.
CHARLES S. RENWICK.
